CLAIM

The ornamental design for a phone float, as shown and described.

DESCRIPTION

FIG. 1 is a front perspective view of a phone float according to the present design;

FIG. 2 is a front elevation view of the phone float of FIG. 1; FIG. 3 is a rear elevation view of the phone float of FIG. 1; FIG. 4 is a left side elevation view of the phone float of FIG. 1;

FIG. 5 is a right side elevation view of the phone float of FIG. 1;

FIG. 6 is a bottom plan view of the phone float of FIG. 1; FIG. 7 is a top plan view of the phone float of FIG. 1;

FIG. 8 is another perspective view of the phone float of FIG. 1; and,

FIG. 9 is a perspective view of the phone float of FIG. 1 positioned on a phone.

The broken lines depicted in FIGS. 1-9 represent unclaimed environmental subject matter and form no part of the claimed design.
